UNITED STATES PATENT OFFICE.

WYLIE G. WILSON, OF ELIZABETH, NEW JERSEY.

APPARATUS FOR FEEDING AND BURNING PREPARED COAL.

1,179,488.

Specification of Letters Patent. Patented Apr. 18, 1916.

Application filed April 29, 1914. Serial No. 835,086.

To all whom it may concern..

Be it known that I, WYLIE G. WILSON, a subject of the King of Great Britain, residing at Elizabeth, in the county of Union and 5 State of New Jersey, have invented certain new and useful Improvements in Apparatus for Feeding and Burning Prepared Coal, of which the following is a specification.

This invention relates to apparatus for use 10 in feeding and burning prepared coal.

While my new apparatus may be and is intended to be used in connection with the burning of what I have designated as pulverized coal, in boiler furnaces or otherwise, 15 yet an important object of my invention is the production of a combustion apparatus or system in which what I have designated as crushed coal may be used as boiler furnace and other fuel; and by crushed coal I mean 20 coal crushed so that it will all pass through screens of from about 5 to 7 mesh. I find that when the crushed coal is of much greater coarseness, the cost of conveyance in automatic apparatus of the kind now shown 25 becomes greater than the cost of crushing the coal to about the coarseness specified; but in thus pointing out the best mode now known to me of practising my invention, I do not intend to limit its use to any degree 30 of fineness or coarseness of the coal used, for I have actually used with success so far as mere combustion is concerned coal crushed to pass through a quarter-inch mesh screen.

From what has been stated, it is obvious 35 that the invention involves and is largely addressed to the practical and economic aspects of coal combustion.

Another object of this invention is to burn coal high in volatile constituents with 40 a minimum of smoke.

In the accompanying drawings forming a part hereof and showing my invention embodied in the best form now known to me,

Figure 1 is an elevation partly in section, 45 through a form of steam boiler, my new furnace, and through some other portions of the apparatus. Fig. 2 is an enlarged view mainly of the batch-conveyer mechanism which forms a portion of the apparatus 50 shown in Fig. 1. This view is partly in elevation and partly in section. Fig. 3 is an enlarged view partly in elevation and partly

in section, and shows speed-controlling mechanism, governing mechanism, and combustion-supporting-air regulating valve 55 mechanism operatively connected together. This mechanism is shown in somewhat smaller scale in Fig. 1. Fig. 4 is a section at line 4-4 of Fig. 5 looking down on the whorl contained in an air-supply conduit. 60 Fig. 5 is in part a transverse section of my new furnace construction at line 5-5 of Fig. 1. Fig. 6 is a view partly in section at a line corresponding to line 6-6 of Fig. 1, showing the slag-basin structure in top plan 65 view and indicating molten slag in the basin. Fig. 7 is a view of another form of apparatus embodying this invention, in which two electric motors and electrical devices are substituted for the two steam engines 70 and for their connections with the steam boiler. Figs. 8 and 9 show still another form of apparatus containing this invention, in which a single motor, which may be of any kind, is substituted for the two steam 75 engines or for the two electric motors.

Referring to the drawings, 1 is a hopper having an outlet 2 which delivers into the feed-hopper 3 of the crushing mill 4 which may be of any suitable type. The mill has 80 a main shaft 5 provided with a belt wheel 6 and is supported on a base 7. The mill also has an eduction pipe 8 the lower end of which discharges into a feed-hopper 8^a within which is mounted an agitator 9, the 85 lower end of the feed-hopper 8^a inclosing a pipe 10 and discharging thereinto. An endless disk-carrying chain 11 provided with disks 12 spaced apart to form a series of pockets *p*, is mounted on sprockets 13 and 13^a, and the peripheries of the disks engage the inner wall of the pipe 10 in their passage therethrough. The chain 11 travels in the direction indicated by the arrow in Fig. 1. The shaft 14 is provided with a spur 90 gear 15 and also with a belt pulley 16 from which a belt 17 extends over a pulley 18 on the shaft 19 of the agitator 9 to drive the agitator.

A worm 20 on shaft 21 meshes with the 95 gear 15 to drive it, and the shaft 21 is provided with a belt pulley 22 from which a belt 23 runs to the belt pulley 24 of the steam engine 25. Pipe 10 is provided with

5 diametrically opposite ports at its tubular extensions 26 and 27. This batch-conveyer comprising the pipe 10, the disk-carrying chain 11, and having the opposite ports at 10 26 and 27, is a form of the invention shown in my United States Patents Nos. 1,048,019, granted to me December 24, 1912, and 1,069,808, granted August 5, 1913.

10 The tubular extension 27 of pipe 10 is connected by an air-pipe 28 with a receiver or header 29, a valve 30 being preferably located in pipe 28. While only one batch-conveyer is shown connected with the header 29, a plurality of them may be connected 15 with it if so desired as will be readily understood, and one engine 25 may be used as will be readily understood, for operating a plurality of the batch-conveyers. The receiver or header is connected 20 by an air-pipe 31 with a pressure blower 32 of any approved construction, and the drive-shaft 33 of which is shown connected by a belt 34 with a pulley 35 on the shaft 36 of a steam engine 37, from the 25 steam-chest 38 of which a steam-pipe 39 leads to the main steam-pipe 40 of the steam oiler 41 the fire-tubes of which are shown by 42. A valve 43 is shown in the steam pipe 39. The smokestack 44 of the boiler 30 furnace 45 is provided with a damper 46 and leads from the front connection 47, the boiler shell 48 resting as usual on the arch 49 of the combustion-chamber 50.

35 The shaft 36 of engine 37 is provided with a belt pulley 51 from which a belt 52 runs to a pulley 53 on the shaft 54 of a fan blower 55, the air-intake of which is indicated by 56. The eduction spout 57 of the casing has attached to it a discharge pipe 58 which is 40 provided with a by-pass pipe 59 which opens into and discharges back into, the air-intake 56 of the fan casing.

45 The admission of air from the fan casing to the by-pass pipe 59 is regulated by the flap valve 60 on a rocker shaft 61 provided with a link 62 to which one end of a pitman 63 is connected, the other end of the pitman being jointed at 64 to a rocker arm 65 which is fixed on the rocker shaft 66, the latter 50 being provided with a rocker arm 67 which is jointed at 68 to one end of a link 69 the other end of which is jointed at 70 to a rocker arm 71 of a valve 72 in a valve casting 73 which is inserted in the length of a 55 steam-pipe 74 leading to the steam-chest 75 of the steam engine 25 from the main steam-pipe 40. A valve 76 is shown located in the steam-pipe 74 adjacent main steam-pipe 40. Steam from the main steam-pipe 40 drives 60 engine 25 and the rocker shaft 66 is automatically actuated by variations of pressure in the boiler 42 to vary the position of the valve 72 which constitutes a speed controller for engine 25, and also to vary the position 65 of the valve 60 which constitutes the com-

bustion-supporting-air regulating-valve of the apparatus, through or by means of the governor device 77 consisting of a tubular casing to which the reference numeral 77 is directly applied, and a piston 78, the piston-rod 79 of which passes through an adjustable plug 80 in the open end of the governor casing 77. A coil spring 81 surrounds the piston-rod abutting at one end against the piston-rod side of the piston 78, and at 75 its other end against the inner end of the adjustable plug 80, adjustments of which vary the tension of the spring. The piston-rod 79 is connected to a rocker arm 82 fixed on the rocker-shaft 66 by the swinging link 83. The governor casing 77 is made solid at its end opposite the adjusting plug 80 and a steam-pipe 84 from a special branch 40^a of the main steam-pipe leads into the pressure-chamber 85 of the governor casing 77. The pipe 84 is provided with a branch pipe 86 to discharge into a steam trap and carry off water of condensation forming in the pressure-chamber 85 and the steam-pipe 84. A valve 87 is shown in pipe 90 84 adjacent the special main-steam-pipe branch 40^a.

90 The combustion-supporting air-pipe 58 leads into the combustion-chamber 50 of the boiler furnace 45, preferably leading vertically downward into the combustion-chamber 50 through the top of the furnace arch 49; and, as shown, the pipe 58 extends upwardly from its connection with the blower fan casing 55 and thence downwardly, its vertical lower end portion forming a mixing-chamber from x to x' (Fig. 1). Preferably the lower end of this mixing-chamber portion of the pipe 58 is flattened on its sides to form an elongated 105 nozzle or discharge-port y' the greater length of which extends in the direction of the length of the arch 49. In the upper part of this mixing-chamber section of the air-pipe 58 I place a whorl 88 which consists of a perforated disk 89 that is slit from a central bore to its periphery, the two free ends of the disk thus formed being offset relatively one to the other to form a part of a helix. When the air under pressure 110 travels downwardly in pipe 58 as indicated by the arrow, it is whirled in its passage through and past the whorl. The whirlwind thus created in the upper part of the mixing-chamber section and traveling downwardly, encounters an up-going current of coal reduced to small particles issuing from the up-turned discharge end 90 of the coal-supply pipe 91, the delivery end of this pipe being entered in the mixing-chamber below 115 the whorl and above its discharge end into the combustion-chamber 50. The coal-conveying pipe leads to the tubular extension 26 of the batch-conveyer pipe 10. 120

125 The bridge wall 92 of the furnace has its 130

usual position extending above fire-brick-work 93 which extends transversely across the furnace as a forward transverse projection of the bridge wall. The front end 5 of the brickwork or transverse wall 93 extends as shown and preferably forwardly of the rear end of the arch 49. This transverse mass of brickwork 93 forwardly of the bridge wall 92 occupies a space in the 10 furnace that is customarily occupied by the rearward portion of grate-bars which are not required in the present furnace construction. The brickwork 93 extends forwardly, forming the bottom and sides of 15 the under blast chamber 95 which corresponds in position to the ordinary ash-pit of a grate-bar furnace. The brickwork 93 is also extended forwardly of its front wall 94 to form the roof 93^a of the under blast 20 chamber 95. Preferably in the new construction parallel T-bars 96 are built in to support the roof portion 93^a of the under blast chamber 95; and where the present invention is incorporated in existing grate-bar boiler furnaces, some or all of the grate-bars may be used to support the roof 93^a in lieu of putting in new ironwork as at 96. The roof 93^a forms the bottom of the combustion chamber 50 and it also constitutes 30 the bottom of a slag basin which is formed by the brickwork 93^a, by the bricks 99 of the combustion chamber, by the wall 94 of the brickwork, and by the front wall portion b of the furnace. This front wall portion of 35 the furnace is suitably perforated at 97 for drawing off the slag, these holes being suitably plugged when required.

The wall 93^a forming the roof of the under blast chamber 95 and the bottom of 40 the combustion chamber 50 and of the slag-basin, is slotted at 98, 98 laterally of the path of the entering current of mixed air and coal from the mixing-chamber section of the air-pipe 58, the discharge-port y' and 45 the wall portion 93^a being spaced apart by the height of the combustion chamber and the slots 98, preferably as shown, extending in the direction of the length of the combustion chamber from the front wall of the 50 furnace to the wall 94 of the brickwork. At the inner side of each slot 98 a ridge of upstanding fire-brickwork 99 is laid on the wall 93^a, and along the outward side of each slot 98 a course 99^a of fire-bricks is 55 laid, each of these courses slanting upwardly and inwardly from an outward edge of the wall 93^a and being spaced apart from the adjacent ridge 99 to form an upwardly and inwardly extending slot, the inner surfaces of the walls being spaced apart to 60 form a slot 100 in registration with the slot 98 in the wall 93^a.

An air-induction nozzle or short tube 101 is inserted through a side wall of the under 65 blast chamber 95, this tube being open at

both ends. Into its outer end portion the steam-nozzle 102 of the steam-pipe 103 leads, discharging centrally and entraining outside air in operation. The steam-pipe 103 leads to the main steam-pipe 40 and is shown 70 provided with a valve 104.

The main steam-pipe 40 is also shown with valves 105. The valves 43, 46, 87, 104 and 105 are ordinary regulating shut-off valves. 75

The governor comprises, as shown in Fig. 3, a stop member 106 which is threaded at 107 through the adjustable plug 80, its inner end extending within the coiled spring 80 and being adapted to limit the movement of the piston in the direction of the plug. The purpose of this stop member is to prevent the coal supply from being wholly shut off in case the spring breaks, or from any other cause, the adjustment of the member limiting the range of movement of the piston. The closed or solid end wall portion of the governor casing is grooved at 108, the steam-pipe 84 entering the pressure chamber 85 at a point removed from the end wall 90 of the casing, and the groove 108 extending lengthwise of the cylindrical portion of the casing and, as shown, partway across the inner surface of the end wall. The purpose of having the steam-pipe 84 enter the pressure chamber 85 at a point removed from the end wall thereof and the purpose of the groove 108, are to form at the solid end of the piston casing a form of dash-pot to prevent the piston from pounding on the end 95 wall of the casing under certain conditions, the groove 108 permitting steam to escape into the space between the piston and the end wall when the piston has moved forwardly so as to cover the inlet end of the 100 pipe 84.

The pipe 101 is preferably provided with an automatic governor valve 109 connected to the rocker-shaft 66 by means of said members 65, 64, 63, 62 and 61, the latter being a rocker-shaft; and by means of the rocker arm 110 on said rocker-shaft 61, the link 111 connecting the outer end of the rocker-arm 110 with a rocker-arm 112 fixed on the rocker-arm 113 of the governor valve 115 or damper 109 which controls the air-inlet 114 of the air-induction nozzle or short tube 101. The furnace is provided with the usual door 97^a above the perforations at 97 through which the molten slag in the slag-basin may be tapped out. 120

The mode of operation is: The coal crusher or reducer 4 is driven by a belt to pulley 6 or in any other suitable manner. The reduced coal passing the agitator flows 125 into the batch-conveyer tube 10 in predetermined quantities depending on the size of the pockets and the speed of the conveyer, the conveyer being driven through the steam engine 25 at a speed which increases as the 130

pressure in steam boiler 41 decreases below the predetermined working pressure of the steam boiler, and which decreases as such pressure increases up to the working pressure, a certain minimum quantity of coal always flowing to the combustion chamber to maintain a flame therein according to the adjustment of the stop 106. These effects are obtained because as the pressure in the boiler increases it pushes the governor piston 78 against the spring 81 and moves the piston-rod 79 so that through its connections with the valve 72 the latter is given a closing movement whereby the flow of steam to the steam engine 25 is reduced and consequently the speed of the batch-conveyer is reduced. On the other hand, decrease of the pressure in boiler 41 permits the spring 81 to push the piston 78 in the reverse direction, giving an opening movement to the valve 72 and so speeding up the batch-conveyer.

The steam engine 37 is run substantially at constant speed so that both the pressure-blower 32 and the fan blower 55 are operated at substantially constant speed. The air-current from the pressure blower supplies an air current which expels the coal charges in the conveyer pockets μ successively through the opposite pipe 91 and forces the reduced coal in the mixing-chamber portion of the air-supply pipe 58 toward the discharge side of the air whorl 88, such discharge side in the present form being the under side of the whorl. The issuing reduced coal is mixed with air for combustion issuing through the whorl and forced thereto by the fan blower 55 through the pipe 58, so that the mixture of air and reduced coal is fed under head to the combustion-chamber.

The valve 60 governs the quantity of air for combustion fed through the pipe 58, this valve 60 being moved, as will be plain from the above description, whenever valve 72 is moved. When valve 72 is given an opening movement to increase the speed of the batch-conveyer, the air-valve 60 is given an opening movement in relation to the air-supply pipe 58 to increase the supply of air for combustion through the pipe 58. When the coal-supply regulating valve 72 is given a closing movement to decrease the speed of the batch-conveyer, the air-supply valve 60 is given a closing movement in relation to the pipe 58 to decrease the combustion air supply through the pipe 58 correspondingly to the decrease of the coal supply. As fan blower 55 delivers a constant volume of air, and as the volume of air supplied to the pipe 58 must be increased or diminished as above explained, the by-pass pipe 59 is closed more or less by the valve 60 during the movements of the latter, with the result of varying the quantity of air delivered to the pipe

58. The return of excess air into the air-intake of the fan blower decreases the power required to drive the fan.

The slag basin and the presence in it of a body of molten slag indicated by S, when the apparatus is in operation, is a very important feature of this invention broadly considered, because the body of molten slag and ash acts to catch the ash formed during combustion, the ash or slag particles being caught on the viscous surfaces of the molten body very much as flies are caught on sticky fly-paper; or as, according to known practice, smoke in passing to a smoke stack is blown against water to cause the latter to catch the unconsumed carbon and ash carried by the smoke. By entrapping the ash on the viscous surface of the molten slag and ash body, such slag and ash are prevented from being carried into the boiler setting and clogging it, and this is an important function and advantage of the slag body. The molten slag body also forms an impinging surface for the flame and thus protects the bottom wall of the combustion chamber from undue and expensive disintegration by the great heat generated in the combustion chamber. And what is also an important function of the slag basin and slag body is that the basin holds the molten ash and slag in fluid condition so that it can be readily tapped out when necessary, through the tap holes, without the labor heretofore required in hoeing or pulling out accumulated ash and slag.

The body of molten slag at its surface especially is maintained at a very high temperature and forms an efficient torch for the ignition of the incoming fuel, constituting a torch of no money value whereas when, as heretofore in such furnaces (not including steam-boiler furnaces however) as pulverized coal has been used in, the hot brickwork kept at a temperature high enough to form an ignition torch, has been disintegrated by heat at the expense of the brickwork which has had to be renewed from time to time.

As stated above, the valve 60 is carried by the rocker shaft 61, and as the valve 60 is moved, the rocker-arm 110 fixed on the rocker-shaft 61 is oscillated, thereby moving the rod 111 and rocker-arm 112 to vary the position of the valve 109 controlling the admission of air into the counter-blast device. Air thus admitted helps to support combustion, and this air supply is regulated automatically correspondingly to the air-supply passing through the pipe 58.

It is not essential that the under blast passing upwardly through the roof of the chamber 95 into the combustion chamber should be a blast of air and of steam, but it is highly desirable that such blast be of air and steam. If air alone is used, it undergoes no change except in temperature and

partial consumption of its oxygen constituent. It of course tends to cool the combustion-chamber walls by reduction of temperature, but its main function in the present 5 apparatus is to keep the coal particles issuing into the combustion chamber through the port y' in longer suspension in the combustion chamber and thus give such particles longer time in which to burn than would 10 be the case if there were no under or counter blast impinging on the fuel-supply blast. Nevertheless, by introducing steam into this counter-blast the same particles-sustaining and cooling effects are obtained and also the 15 steam is dissociated into oxygen and hydrogen, both of which are combustible, and this is advantageous. It is conceivable that in some cases steam alone might be used for the counter-blast.

20 While this invention has been thus far described with particular reference to steam boiler furnaces, the invention in whole or in part is applicable to locomotive engines as well as to steam boilers of the stationary type 25 shown in the drawings, and I consider the method herein described of holding reduced coal in suspension while it is burning in a combustion chamber as having a wide range of practical utility in various forms of combustion apparatus, and I also consider the 30 slag basin and the body of molten slag as having a wide range of practical utility in combustion apparatus. Each of these features is broadly new with me so far as I am 35 advised, and when used in conjunction one with the other as explained, are of great demonstrated value especially in connection with the burning of what I have described as crushed coal, which of course includes in 40 its volume what I have called pulverized coal.

In the foregoing description I have referred to the use of two steam engines 25 and 37, and the use of two separate steam 45 engines is, from a practical engineering standpoint, better than the use of one steam engine doing the work of the two steam engines 25 and 37. But one steam engine may be used if desired in lieu of the two and I 50 have shown such form of installation as a varying form of my invention.

While the use of the steam engines 25 and 55 37 is preferred to the use of one steam engine, yet it is perfectly feasible to substitute one or more electric motors with appropriate 60 connections for one or both of the steam engines, and in Fig. 7 I have shown the electrically-actuated mechanism which for the purposes of this invention constitutes a full 65 mechanical equivalent of the steam-engine installation. Herein in lieu of steam engines 25 and 37 and the steam pipes 39 and 74, and the governor valve 73 in the pipe 74, I show electric motors M and M', the 75 motor M being a variable-speed motor wired

at m to a controlling rheostat m' of known construction. The rheostat is wired at m^2 to a source m^3 of electricity which is wired at m^4 to the motor M'. Otherwise the apparatus is the same as that described, except 70 that the rheostat contact lever m^5 is connected by a link m^6 to the lever 82.

In Figs. 8 and 9 I show how one motor of any kind, electric, steam, or otherwise, may be employed to perform the function of the steam engines 25 and 37 and of the steam pipes 39 and 74 including the governor-valve device 73. In these figures the batch-conveyer shaft 14 is provided with a friction disk b which is rotated by a friction wheel c on a shaft d provided with a bevel gear d' with which meshes a bevel gear d^2 on a shaft d^3 . This shaft is provided with belt pulleys d^4 , d^5 . From pulley d^4 a belt d^6 runs to a pulley d^7 on the power shaft of a motor E which may be of any desired kind or which may be considered as a source of power of any kind, the shaft d^3 being the power shaft of this form of the invention, and the shaft being provided with a pulley d^8 from which a belt d^9 runs to a pulley d^{10} on the shaft of the pressure blower 32. From the pulley d^5 on the power shaft a belt f runs to pulley f' on the shaft of the fan blower. Otherwise the apparatus is the same 95 as that described for the preferred form of the invention.

In all forms of my invention the great heat of the molten slag body performs an active function which in some installations 100 renders it wholly unnecessary to employ any counter-blast of any kind. Such function is to retard the inflow of the fuel mixture through the port y' by what may be called heat-repulsion, and to raise almost instantaneously on its escape from the port y' much of the fuel to a state of combustion. It is to be added that if and when any of the unburned coal particles fall into the molten slag body they are almost instantly burned. 110

While some air is in mixture with the coal in the batch-conveyer pockets and through the coal-supply pipe 81, yet I find in practice that it is desirable to mix the coal with air for combustion, adjacent the feed-in port y' , 115 and that the proper mixture is obtained by forcible interaction of the coal and air which is most simply obtained near the port y' by means of the whirl.

The parallel, upwardly and inwardly inclined passages 100, one at one side portion and the other at the other side portion of the wall 93^a direct to counter-blasts in converging currents upward toward the feed-in port y' , and tend to push the entering fuel mixture toward the arch, thereby tending to confine the fuel mixture between the molten slag body and the arch, or in other words to cause the fuel to be burned in suspension. It is desirable that 130

the finer and the coarser particles of the reduced coal be intimately mixed in order that the finer particles first raised to a state of combustion may fire the larger particles.

It is to be said further that no one so far as I know has heretofore successfully burned as a type of fuel or as a regular fuel body what I have herein designated 10 as crushed coal, or coal of approximately the size stated.

It is not desired to maintain any particular pressure in the combustion chamber.

While the foregoing specification shows 15 and describes in detail a construction of one form of furnace in connection with a steam boiler, it is to be understood that this invention broadly considered is not confined to the operation of steam boilers, but 20 may be embodied or used in all processes involving the treatment of solid fuel finely divided, and that it is applicable for example to various types of furnaces used in metallurgical processes; and that the automatic regulation of the functions of the 25 apparatus may as well be in accordance with variation of temperature at any given point as with the variation of pressure in a steam boiler resulting from the variation 30 of temperature of the gas passages surrounding said steam boiler.

What I claim is:

1. The combination of a steam boiler with a furnace comprising a pipe for feeding 25 under head mixed air and coal into the combustion chamber of the furnace; and means for delivering into the combustion chamber a gaseous volume under head and opposed to the incoming mixture of coal 40 and air, whereby the fuel charge in a state of combustion is maintained in suspension in the atmosphere of the combustion chamber; said pipe connecting with an air supply conduit provided with an interior whirl 45 and also connecting with a fuel supply conduit which delivers into said pipe adjacent the mouth of the air supply conduit and within the field of the whirling air issuing from the whirl.

2. The combination of a steam boiler with a furnace comprising a pipe for feeding under head mixed air and coal into the combustion chamber of the furnace; means for delivering into the combustion chamber 50 a gaseous volume under head and opposed to the incoming mixture of coal and air, whereby the fuel charge in a state of combustion is maintained in suspension in the atmosphere of the combustion chamber; the discharge end of the pipe for feeding the air and coal mixture discharging through the top wall of the combustion chamber; and said means being constructed to discharge said gaseous volume through the 55 bottom wall of the combustion chamber.

ber, said pipe connecting with an air supply conduit provided with an interior whirl and also connecting with a fuel supply conduit which delivers into said pipe adjacent the mouth of the air supply conduit and within the field of the whirling air issuing from the whirl. 70

3. The combination of a steam boiler with a furnace comprising a pipe for feeding under head mixed air and coal into the combustion chamber of the furnace; means for delivering into the combustion chamber a gaseous volume under head and opposed to the incoming mixture of coal and air, whereby the fuel charge in a state of combustion is maintained in suspension in the atmosphere of the combustion chamber; and a slag basin containing molten slag at the bottom of the combustion chamber; the furnace having a chamber beneath the combustion chamber and a partition between the chambers; the partition having a pair of parallel slots at the inward side of each of which is a ridge and at the outward side of each of which is an upwardly and inwardly inclined course of suitable material, the opposed surface of each course and the adjacent ridge being spaced apart to form a continuation of one of said slots. 85

4. The combination of a steam boiler furnace; an air-supply pipe; a whirl in said pipe; a fuel-supply pipe entering the air-supply pipe and arranged to discharge toward the discharge side of the whirl; said pipes being constructed to deliver coal and air in mixture under head to the combustion chamber of the furnace; and means for discharging a gaseous volume under head into the combustion chamber in opposition to the fuel-supply discharge. 90

5. The combination of a steam boiler and furnace; an air-supply pipe; a whirl in said pipe; a fuel-supply pipe entering the air-supply pipe and arranged to discharge toward the discharge side of the whirl; said pipes being constructed to deliver coal and air in mixture under head to the combustion chamber of the furnace; means for discharging a gaseous volume under head into the combustion chamber in opposition to the fuel-supply discharge; and a slag basin at the bottom of the combustion chamber. 110

6. The combination of mechanism for reducing coal; mechanism for conveying it in batches; means for mixing the reduced coal with air to form a fuel mass under head; means for discharging the fuel under head into the combustion chamber of a furnace; and devices for maintaining in the combustion chamber a gaseous volume under head and opposed as a current to the intake of the fuel mixture, a furnace and a steam boiler; said mixing means comprising an air whirl for whirling the air prior to its intermix- 120 125 130 135

ture with the fuel, and the furnace having its bottom constructed to contain a mass of molten slag to withstand the heat thereof and to permit the upward passage of the 5 current opposed to the intake of the fuel mixture.

7. The combination of mechanism for reducing coal; mechanism for conveying it in batches; means for mixing the reduced coal 10 with air to form a fuel body under head; means for discharging the fuel under head into the combustion chamber of a furnace; and devices for maintaining in the combustion chamber a gaseous volume under head 15 and opposed as a current to the intake of the fuel mixture; said conveying mechanism and means being constructed to exclude from the presence of the coal all air other than that mixed with the coal to support 20 combustion, a furnace and a steam boiler; said mixing means comprising an air whirl for whirling the air prior to its intermixture with the fuel, and the furnace having its bottom constructed to contain a mass of 25 molten slag to withstand the heat thereof and to permit the upward passage of the current opposed to the intake of the fuel mixture.

8. The combination of a steam boiler with 30 a furnace comprising a pipe for feeding under head mixed air and coal into the combustion chamber of the furnace; and means for delivering into the combustion-chamber a gaseous volume under head and opposed 35 to the incoming mixture of coal and air, whereby the fuel charge in a state of combustion is maintained in a state of suspension in the atmosphere of the combustion-chamber; said pipe connecting with an air- 40 supply conduit provided with an interior whirl and also connecting with a fuel-supply conduit which delivers into the said pipe adjacent the mouth of the air-supply conduit and within the field of the whirling 45 air issuing from the whirl; the bottom of the furnace being constructed to hold and withstand the heat of a body of molten slag.

9. The combination of a steam boiler with 50 a furnace comprising a pipe for feeding under head mixed air and coal into the combustion chamber of the furnace; means for delivering into the combustion chamber a gaseous volume under head and opposed to 55 the incoming mixture of coal and air, whereby the fuel charge in a state of combustion is maintained in suspension in the atmosphere of the combustion chamber; the discharge end of the pipe for feeding the air 60 and coal mixture discharging through the top wall of the combustion chamber; and said means being constructed to discharge said gaseous volume through the bottom wall of the combustion chamber; said pipe connecting with an air-supply conduit provided

with an interior whirl and also connecting with a fuel-supply conduit which delivers into said pipe adjacent the mouth of the air-supply conduit and within the field of the whirling air issuing from the whirl; the 70 bottom of the furnace being constructed to hold and withstand the heat of a body of molten slag.

10. The combination of a steam boiler with a furnace comprising a pipe for feeding under head mixed air and coal into the combustion-chamber of the furnace; means for delivering into the combustion-chamber a gaseous volume under head and opposed to the incoming mixture of coal and air whereby the fuel charge in a state of combustion is maintained in suspension in the atmosphere of the combustion chamber and a slag basin containing molten slag at the bottom 80 of the combustion chamber; the furnace having a chamber beneath the combustion chamber and a partition between the chambers; the wall of the combustion chamber being formed with an opening for admission from the under chamber of the volume opposed to said incoming mixture of coal and air; such opening being removed from the molten-slag-holding walls of the slag basin.

11. The combination of a steam boiler with a furnace comprising a pipe for feeding under head mixed air and coal into the combustion-chamber of the furnace; means for delivering into the combustion-chamber a gaseous volume under head and opposed to the incoming mixture of coal and air whereby the fuel charge in a state of combustion is maintained in suspension in the atmosphere of the combustion chamber and a slag basin containing molten slag at the bottom 90 of the combustion chamber; the furnace having a chamber beneath the combustion chamber and a partition between the chambers; the wall of the combustion chamber being formed with an opening for admission from the under chamber of the volume opposed to said incoming mixture of coal and air; such opening being removed from the molten-slag-holding walls of the slag basin.

12. The combination of a steam boiler with a furnace comprising a pipe for feeding under head mixed air and coal into the combustion chamber of the furnace; a stationary device for giving a whirling motion to the mixture; means for delivering into the combustion chamber a gaseous volume under head and opposed to the incoming whirling mixture of coal and air whereby the fuel charge in a state of combustion is maintained in suspension in the atmosphere of the combustion chamber, the bottom 100 of the combustion chamber being constructed with an opening for admission from the under chamber of the volume opposed to said incoming mixture of coal and air; such opening being removed from the molten-slag-holding walls of the slag basin; and a stationary air-whirl for the air mixed with coal fed into the combustion chamber.

125

13. The combination of a steam boiler with a furnace comprising a pipe for feeding under head mixed air and coal into the combustion chamber of the furnace; a stationary device for giving a whirling motion to the mixture; means for delivering into the combustion chamber a gaseous volume under head and opposed to the incoming whirling mixture of coal and air whereby the fuel charge in a state of combustion is maintained in suspension in the atmosphere of the combustion chamber, the bottom 120 of the combustion chamber being constructed to hold and resist the heat of a therein-contained body of molten slag and

being also constructed with an opening for delivery into the combustion chamber of the volume opposed to said incoming mixture of coal and air, such opening being removed from the wall surfaces holding the molten slag body; and said molten slag body.

5 In testimony whereof I have hereunto set

my hand in the presence of two subscribing witnesses, this 28th day of April, 1914.

WYLIE G. WILSON.
